BACKPLATE FOR DOOR PULLS AND THE LIKE

Leo Jiranek, New York, N.Y., assignor to Bassett Furniture Industries, Bassett, Va.

Filed Oct. 16, 1961, Ser. No. 67,087

Term of patent 14 years

(Cl. D10—8)

FIG. 2

FIG. 3

FIG. 4

FIG. 5

FIG. 1 is a front view of a backplate for door pulls and the like embodying my new design;

FIG. 2 is an end elevational view;

FIG. 3 is a vertical sectional view taken in the direction of the arrows 3—3 of FIG. 1;

FIG. 4 is a horizontal sectional view taken in the direction of the arrows 4—4 of FIG. 1; and

FIG. 5 is a horizontal sectional view taken on the line 5—5 of FIG. 1.

The rear not shown is substantially plain and is intaglio where the front is in relief as best indicated in the cross sectional views.

I claim:

The ornamental design for a backplate for door pulls and the like, as shown and described.
